STORAGE CABINET FOR SOFT DRINK CRATES

Harvey J. Smith, Greensboro, N.C., assignor to Modern Metal Products Company, Greensboro, N.C., a corporation of North Carolina

Filed Oct. 2, 1963, Ser. No. 76,836

Term of patent 14 years

(Cl. D80—11)

FIG. 1

FIG. 2

FIG. 1 is a front perspective view taken from one side of a storage cabinet for soft drink crates embodying my new invention;

FIG. 2 is another front perspective view taken from the side opposite that shown in FIG. 1, doors being in an open position;

FIG. 3 is a reduced scale top plan view thereof; and

FIG. 4 is a reduced scale rear elevational view thereof.

What I claim is:

The ornamental design for a storage cabinet for soft drink crates, as shown.
